Patented Jan. 19, 1926.

UNITED STATES PATENT OFFICE.

THOMAS S. GOFF, OF MARTIN, TENNESSEE.

SAFETY RAZOR.

Application filed July 19, 1923. Serial No. 652,576.

To all whom it may concern:

Be it known that I, THOMAS S. GOFF, a citizen of the United States, residing at Martin, in the county of Weakley and State of Tennessee, have invented certain new and useful Improvements in Safety Razors, of which the following is a specification.

This invention relates to safety razors and has for its object the provision of a razor which may be produced at a less cost than razors now on the market, which may be used with equal facility in either hand, and by which a close comfortable shave may be obtained with a draw cut in the same manner as in the use of an ordinary razor. One embodiment of my invention is illustrated in the accompanying drawings, and the invention resides in certain novel features which will be particularly pointed out in the claims following the detailed description.

In the drawings:

Figure 1 is a plan view of a safety razor constructed according to my invention;

Fig. 2 is a side elevation of the same;

Fig. 3 is a central longitudinal section;

Fig. 4 is a detail plan view of the guard;

Fig. 5 is an enlarged end view of the device, and

Fig. 6 is a detail plan view of the blade.

In carrying out my invention I employ a base which is arcuate in form, as shown in Figure 5, and from one end of which extends a handle 2, the said handle being knurled or otherwise roughened, as indicated at 3, whereby a firm grip may be easily obtained. The handle extends along the longitudinal axis of the base and is preferably formed integral therewith so that the device may be held in the same manner as an ordinary razor is held and the blade manipulated to obtain a draw cut upon the beard, as will be readily understood. The base is provided with openings therethrough along its medial longitudinal line and one of said openings is located close to the end of the handle to receive a stud 4, the opening being slightly countersunk on the under side of the base so that the end of the rivet may be upset and the protruding portion of the same removed by the use of any convenient and efficient tool so that a smooth flush surface will be provided on the bottom of the base. The stud is constructed with an an-

nular shoulder as indicated at 5 whereby the insertion of the stud in the opening provided therefor will be limited and the stud permitted to project above the base to the proper extent, the circumferential surface of the stud being smooth so that the blade and the guard may be easily fitted thereover. The other opening in the base is located near the free end of the same and receives a stud or post 6 which is at its upper extremity, threaded, as shown at 7, to receive a thumb nut 8 whereby the blade and the guard may be clamped to the base, the remaining portion of the post or stud being smooth so that injury will not be caused to the post nor to the blade nor the guard in assembling the parts. The blade 9 is a flexible metal plate of proper form and dimensions to fit upon the base and to project somewhat beyond the side edges of the same, as shown in Fig. 5, the side edges of the blade being sharpened, as indicated at 10. The blade is provided with openings 11 and 12 to fit over the stud 4 and the post 6 as will be readily understood and the guard 13 is provided with similar openings 14 and 15. The guard consists of a metal plate approximately the same thickness as the base 1 and given a permanent arcuate form corresponding to the arcuate form of the base so that when the guard is placed in position on the blade and the nut 8 turned home, the blade will be flexed and firmly secured with its cutting edges in rectilinear lines. Along its side edges the guard is constructed with teeth 16, the extremities of which extend beyond the cutting edges of the blade in the usual manner.

In assembling the parts for use, the blade is first engaged over the stud 4 and the post 6 and the guard is then engaged over said elements so as to rest upon the blade. The thumb nut 8 is then engaged upon the post and turned home against the guard so as to secure and flex the blade against the base, as shown and as will be readily understood. If the nut be turned fully home, the edges of the blade will be in close contact with the teeth of the guard and cutting of the flesh will be thereby positively avoided. If, however, a particularly close shave is desired, the nut may be slightly loosened whereupon the blade will be unflexed to some degree and its edges will be spaced slightly from the teeth of the guard so that the blade

may then cut the beard closer to the skin. It will be noted that one side of the handle 2 is disposed in the same longitudinal plane with the bottom of the base 1 and forms a continuation thereof, while the other side of said handle is disposed in a plane above or in advance of the top of the thumb nut 8. By forming the handle and base in this manner said base in conjunction with the handle provides a continuous flat surface for the razor when it is placed on a table or other support and should the razor be placed on the table in a reverse position, that is to say, upside down the thumb nut 8 can not come in contact with the table owing to the fact that the upper side of the handle projects beyond the same and forms, in effect, a housing for the thumb nut. It will also be noted that the inner end of the handle at its junction with the base is expanded laterally and inclined or beveled in the direction of the base 1 so as not to offer any surface projection while at the same time assisting in shedding or deflecting any lather which may accumulate thereon during the shaving operation.

It will be readily noted from the foregoing description, taken in connection with the accompanying drawings, that I have provided an exceedingly simple razor which may be produced at a low cost and which may be assembled for use quickly and may be disassembled and cleaned with facility. My improved safety razor may be handled in the same manner as the ordinary razor is usually handled so that no fatigue will follow from its use and it may be used in either hand.

Having thus described my invention, what is claimed is:

1. A safety razor comprising a base having a solid handle of uniform diameter projecting from one end thereof with one side of said handle disposed in the same longitudinal plane with the bottom of the base for the entire length of said handle and forming a continuation of the base, the other side of the handle at its junction with the base being expanded laterally and inclined in the direction of said base, a cutting blade carried by the base, a guard fitting over the blade, and means for clamping the guard and blade in position on the base, the clamping means lying wholly inwardly of a longitudinal plane touching the last-mentioned side of the handle.

2. A safety razor comprising a transversely curved base having a solid handle of uniform diameter projecting from one end thereof with one side of said handle disposed in the same longitudinal plane with the bottom of the base for the entire length of said handle and forming a continuation of said base, studs rising from the base, one of which is threaded, a blade having openings to receive said studs, a guard resting on the blade and through which the studs project, and a thumb nut engaging a threaded stud for clamping the blade and guard in position on the base, the outer surface of the thumb nut lying wholly inwardly of a longitudinal plane touching the other side of the handle.

In testimony whereof I affix my signature.

THOMAS S. GOFF. [L.S.]
